Primary Examiner — Jonathan J Han(74) Attorney, Agent, or Firm — Banner & Witcoff, Ltd.(57) CLAIM

The ornamental design for a shoe, as shown and described.

DESCRIPTION

FIG. 1 is a front perspective view of a shoe showing my new design;
FIG. 2 is a side view thereof; and,

FIG. 3 is a rear perspective view thereof.

The broken lines depicting the remainder of the shoe form no part of the claimed design.
